RAILWAY TRAFFIC CONTROLLING
APPARATUSJohn M. Pelikan, Chicago, Ill., assignor to The
Union Switch and Signal Company, Swissvale,
Pa., a corporation of Pennsylvania

Application May 16, 1942, Serial No. 443,240

14 Claims. (Cl. 246—38)

My invention relates to railway traffic controlling apparatus, and it has particular reference to the organization of such apparatus into traffic controlling systems of the type in which code impulses of energy transmitted over either or both line and track circuits are utilized for effecting a control or controls.

In general, it is proposed in accordance with my invention to provide novel and improved forms of railway traffic controlling systems of the type employing code impulses of energy. More specifically, it is proposed to provide railway traffic controlling systems incorporating novel and improved means for generating the code impulses of energy transmitted over the control circuits.

In systems utilizing code impulses of energy, it is customary to employ code transmitters or coders which operate contacts and are effective to cause the energy in a pair of conductors of a control circuit to be periodically interrupted or coded in such manner as to provide in such circuit alternate "on" and "off" periods during which current does and does not flow, respectively. It has been proposed to utilize coded current generated by a coder and supplied to a pair of conductors to generate in turn other coded current supplied to the said pair of conductors, thus causing a control circuit to be supplied with two sets of code impulses, one set comprising a normal or "master" code generated by the coder and causing operation of a code following relay, and the second set comprising a reverse or "feed back" code generated by the action of the master code following relay and operative to cause operation of a feed back code following relay. It is an object of my invention to extend the self-generating feature of this arrangement by providing means for eliminating the necessity for a code transmitter, thereby providing a code system wherein each one of the two sets of code impulses applied to a pair of conductors is generated in response to the other set of code impulses.

Another object of my invention is to provide a code system of signaling wherein the necessity for a code transmitter or coder is obviated by arranging the code responsive apparatus at the two ends of a circuit in such a manner that each code following relay generates and supplies to the circuit a code impulse in response to each impulse of code received by the relay from the circuit.

An additional object of my invention is the provision of novel and improved detector circuits

employing code impulses of relatively short duration.

A further object is to provide novel and improved detector circuits employing code impulses of energy and arranged to be self-checking so that if any portion of the apparatus fails to operate properly, the coding action is terminated.

An additional object of my invention is to provide novel and improved detector circuits employing code impulses of energy and arranged to be immune to false current.

In practicing my invention, the above-mentioned and other important objects and characteristic features which will become readily apparent from the following description, are attained by providing a pair of conductors with two energy sources and with two polarity responsive relays, and by energizing both of the relays simultaneously by energy derived alternately from first one and then the other of the two sources, the two sources being poled in opposition to each other so as to reversibly energize the relays.

I shall describe several forms of apparatus embodying my invention, and shall then point out the novel features thereof in claims.

In the accompanying drawings, Fig. 1 is a diagrammatic view representing one form of apparatus embodying my invention applied to a control circuit of the track circuit type. Figs. 2, 3 and 4 are each diagrammatic views representing modified forms of the apparatus illustrated in Fig. 1. In each of the several views, similar reference characters have been employed to designate corresponding parts.

Referring to Fig. 1, the reference characters 1 and 1a designate the track rails of a stretch of railway track divided by insulated joints 2 into a plurality of successive adjoining track sections of which only one section, D—E, is represented complete in the drawings. The rails 1 and 1a of section D—E comprise the transmission conductors of a control circuit of the track circuit type in which the conductors are ordinarily effective to transmit energy from either end of the circuit to the other, but which conductors at times are rendered ineffective to transmit such energy.

The circuit of section D—E is provided with two sources of unidirectional energy, designated 50 by the reference character TB with suitably distinguishing prefixes, and with two track relays, designated by the reference character TR with suitably distinguishing prefixes. Each of the relays TR is a polarity responsive relay of the polar stick type and has an armature operable to one

extreme position or another according as the relay is energized by current of one relative polarity or the other.

Relay WTR has associated therewith two slow releasing relays, designated by the reference characters FSA1 and HR1, respectively, and a polar stick relay M. Relay FSA1 is provided with a pick-up circuit which extends from one terminal B of a suitable source of current, such as a battery not shown but having its opposite terminals designated in the drawings by the reference characters B and C, through polar contact 5 closed in the reverse or right-hand position, as viewed in the drawings, of the polar armature of relay WTR, polar contact 6 closed in the normal or left-hand position of relay M, and the winding of relay FSA1 to terminal C. Relay FSA1 also is provided with an auxiliary circuit in which front contact 7 of relay HR1 provides an alternate path around polar contact 6 of relay M. The other slow releasing relay HR1 is provided with an energizing circuit which may be traced from terminal B through polar contact 5 of relay WTR closed in its normal or left-hand position, front contact 10 of relay FSA1, and the winding of relay HR1 to terminal C. Relay M is a two-winding relay provided with a normal energizing circuit which extends from terminal B through normal polar contact 9 of relay WTR and one portion of the winding of relay M to terminal C; with a reverse energizing circuit which extends from terminal B through reverse polar contact 9 of relay WTR, front contact 11 of relay FSA1 and the other portion of the winding of relay M to terminal C; and with an auxiliary circuit which extends from terminal B through reverse polar contact 9 of relay WTR, back contact 11 of relay FSA1, back contact 12 of relay HR1 and the said one portion of the winding of relay M to terminal C.

Relay ETR is provided with a slow releasing repeater or impulse generating relay ETPR energized over an obvious circuit which includes terminal B, polar contact 15 of relay ETR closed in its normal or left-hand position, the winding of relay ETPR and the other terminal C. Relay ETR may also be provided, as shown, with a slow releasing relay FSA2 energized over polar contact 18 of relay ETR closed in its normal position, and with another slow releasing relay HR2 energized over an obvious circuit including reverse polar contact 18 of relay ETR and a front contact of relay FSA2.

In the normal condition of the apparatus, section D-E is unoccupied and relays ETR and WTR are energized in series, by energy derived alternately from the two sources TB. Battery WTB, for example, energizes both relays WTR and ETR in series over a first track circuit extending from one terminal of battery WTB through normal polar contact 16 of relay M, rail 4, front contact 17 of relay ETPR, the winding of relay ETR, rail 4a, and the winding of relay WTR to the other terminal of battery WTB. This track circuit is completed when relay M is in its normal position due to the energization of the relay over its normal circuit including normal polar contact 9 of relay WTR, and when relay ETPR is energized over its obvious circuit including contact 15 of relay ETR. The polarity of current supplied from battery WTB to the relays WTR and ETR over the first track circuit is such as to cause the relays to shift their respective armatures from the illustrated positions to the reverse or right-hand positions, whereupon relay

ETPR becomes deenergized, and relay M is caused to shift its polar armature to its reverse position, thereby opening or interrupting the first track circuit by disconnecting battery WTB from the track rails and relays WTR and ETR. Relay ETPR releases, at the end of its release period, and opens its front contact 17 to open the first track circuit at that point. Back contact 17 of relay ETPR now closes to connect battery ETB to relays ETR and WTR in series over a second track circuit extending from one terminal of battery ETB through back contact 17 of relay ETPR, rail 4, reverse polar contact 16 of relay M, the winding of relay WTR, rail 4a, the winding of relay ETR and to the other terminal of battery ETB. The polarity of current supplied from source ETB to the relays over the second track circuit is the reverse of that supplied from battery WTB to the first track circuit and causes the relays to shift their respective armatures back to their normal positions, whereupon relay ETPR becomes energized and immediately picks up to open the second track circuit by disconnecting battery ETB from the track rails and the track relays, while relay M becomes energized over its normal circuit and shifts its polar contact 16 to its normal position. The opening of reverse contact 16 opens the second track circuit and the closing of normal polar contact 16 completes the first track circuit by connecting battery WTB in circuit with both relays WTR and ETR. This cycle of operation continues as long as section D-E is vacant, hence relays WTR and ETR are energized in series alternately first by current of one polarity derived from battery WTB and supplied over a first track circuit and then by current of the opposite polarity derived from battery ETB and supplied over a second track circuit. Each one of these sources is connected in circuit with the track rails and relays for relatively short intervals of time in response to an impulse of energy received from the other of such sources, with the result that each source of energy is caused to supply coded energy to the rails in response to code impulses of energy supplied from the other of the sources to the rails. It follows, therefore, that I have provided a control circuit scheme in which a set of code impulses supplied to a pair of conductors causes a second set of code impulses to be supplied to the conductors for in turn effecting the generation of the first set of code impulses. The two sets of code impulses supplied respectively to the two conductors are, therefore, caused to be mutually self-generated.

The operation of track relays WTR and ETR in response to the self-generated code impulses is detected by means of the associated slow acting relays FSA and HR. Relay FSA1, for example, becomes energized when reverse polar contact 5 and normal polar contact 6 of relays WTR and M, respectively, are closed, and picks up to close its front contact 10 and prepare a circuit for relay HR1, which circuit becomes completed when normal contact 5 of relay WTR closes. When relay HR1 picks up, another circuit for relay FSA1 is prepared, including reverse contact 5 of relay WTR and front contact 7 of relay HR1, hence when relay WTR operates its polar armature alternately to first one and then the other position, relays FSA1 and HR1 are alternately energized. These relays are provided with slow releasing periods, attained in part at least by means of resistors 19 connected across their terminals, selected to maintain the relays in their

picked-up positions for intervals which bridge the intervals that their respective energizing circuits are open due to the operation of the polar contacts of relays WTR and M. Similarly, relays FSA2 and HR2, associated with relay ETR, are both picked up when relay ETR is caused to reversibly operate its polar armature.

When a train enters the section, relay ETR either remains in or assumes its normal position, while relay WTR either assumes or remains in its reverse position. In other words, with a train in the section, the two track relays are caused to operate their polar armatures to positions out of correspondence. For example, if a train enters the section when battery WTB is connected to the track rails, the train shunt established in the section prevents relay ETR at the opposite section end from responding to such energy, hence relay ETR remains in its normal position and relay ETPR is maintained energized. Relay FSA2 also remains energized, while relay HR2 releases at the end of its slow release period to indicate that relay ETR is no longer reversibly operating its polar armature. Relay WTR, on the other hand, becomes energized in series with the train shunt and operates its polar armature to its reverse position, thereby reversing the energization of relay M, which relay operates its polar armature in turn to disconnect battery WTB from the track rails. Relay WTR remains in its reverse position since no energy impulse of the opposite polarity is at this time impressed on the track rails, and relay HR1 first releases to open its front contact 7 whereupon relay FSA1 also releases. Relay M, however, now becomes energized by current of normal polarity over its auxiliary circuit including reverse polar contact 9 of relay WTR and back contacts 11 and 12 of relays FSA1 and HR1, respectively, whereupon normal polar contacts 6 and 16 of relay M close. Relay WTR now becomes energized again in series with the train shunt, by current of the polarity corresponding to the reverse position of the relay, but no operation of relay WTR is effected by this current since the relay already is in its reverse position. Relay FSA1, however, picks up over its pick-up circuit including reverse contact 5 and normal contact 6 of relays WTR and M, respectively, and back contact 11 of relay FSA1 opens to interrupt the previously traced auxiliary circuit. Front contact 11 of relay FSA1 is now closed to complete the reverse circuit of relay M, whereupon the polar contacts of that relay reverse to disconnect battery WTB from the track rails, and to deenergize relay FSA1. When that relay drops, relay M again becomes energized by current of normal polarity and shifts its polar contact members 6 and 16. This operation of relays M and FSA1 continues as long as the train shunt is maintained in the section.

The relays M and FSA1 cooperate in providing what I shall term code initiating means effective after the section becomes vacant to restore the apparatus of the section to its normal condition wherein the code impulses supplied to the two track circuits of the section are each caused to be generated by the action of the code impulses supplied to the other circuit. This restoration is effected when the train vacates section D-E and the energy applied by battery WTB to the track rails, during the interval when relay M is in its normal condition, is no longer shunted away from relay ETR. Thus, for example, when the train vacates section D-E, contact 16 of re-

lay M may be either in its normal or its reverse position. If contact 16 is in its reverse position, battery WTB is disconnected from the track rails and both relays WTR and ETR maintain their respective contacts in their last operated positions wherein the contacts are out of agreement. Then, after relay M is caused to operate its contacts to their normal positions in the manner pointed out hereinbefore (or if contact 16 is in its normal position when the train vacates section D-E), battery WTB is connected with the track rails and it energizes relay ETR to cause that relay to operate its contact 15 to its reverse or right-hand position to deenergize relay ETPR. This latter relay in turn releases to open at front contact 17 the previously mentioned first track circuit, and closes its back contact 17 to connect battery ETB to the track rails. At the opposite end of the section, relay FSA1 was picked up when relay M operated to its normal position, so that relay M is energized over its reverse position and operates its contact 16 to its reverse position. The polar armatures of relays WTR, ETR and M now occupy corresponding relative positions and the second track circuit is established whereupon both relays WTR and ETR are energized by battery ETB and operate their respective contacts to their normal positions. Relays HR1 and HR2 are now caused to pick up, and the apparatus of Fig. 1 is restored to its normal condition, as indicated in the drawings, wherein the two track relays are caused to be reversibly operated. It follows, therefore, that due to the interaction of relays FSA1 and M in causing the rails to be intermittently supplied with energy impulses when the section is occupied, there is available in the section when it becomes vacant an initiating code impulse effective to restore the track circuit apparatus to its normal condition. After the track circuit apparatus is restored to normal, relay FSA1 is held constantly energized and the interaction of relays FSA1 and M ceases.

In an alternative form of the apparatus, represented in Fig. 2, relay WTR has associated therewith its track battery WTB, a slow releasing repeater relay AR energized over an obvious circuit including normal polar contact 5 of relay WTR, a resetting coder relay RCR energized over an obvious circuit including its own contact 20 and back contact 21 of relay AR, and a slow pick-up track repeater relay WTPR energized over an obvious circuit including normal polar contact 9 of relay WTR. Relay ETR has associated therewith its battery ETB, and relay ETPR is energized over its obvious circuit including normal polar contact 15 of relay ETR.

The apparatus of Fig. 2 operates as follows: When the section is unoccupied, relays WTR and ETR are energized, in series, by current alternately supplied first from one battery over one track circuit and then from the other battery over another track circuit. For example, I shall assume that the apparatus is in the condition represented in Fig. 2, that is, the normal polar contacts of track relay ETR and the reverse polar contacts of track relay WTR are closed, respectively, repeater relay ETPR is energized, while relay AR is deenergized but is held up in its picked-up position due to its slow release characteristics. Under the assumed conditions, relays ETR and WTR are energized in series over a circuit extending from one terminal of battery ETB through rail 1a, back contact 22 of relay ETPR, back contact 23 of relay RCR, the wind-

ing of relay WTR, rail 1, the winding of relay ETR and front contact 17 of relay ETPR to the other terminal of battery ETB.

The polarity of current supplied from battery ETB to relays ETR and WTR at this time is such that relay ETR is caused to swing its polar contacts to their reverse or right-hand positions, while relay WTR is caused to operate its contacts to their normal or left-hand positions. Relay ETPR accordingly becomes deenergized and drops to disconnect battery ETB from the track relays, and relays WTPR and AR become energized. Relay AR is held up by energy in its normal picked-up position, and relay WTPR picks up at the end of its slow pick-up period to complete a circuit extending from one terminal of battery WTB through rail 1a, back contact 17 of relay ETPR, the winding of relay ETR, rail 1, the winding of relay WTR, back contact 23 of relay RCR and front contact 22 of relay WTPR to the other terminal of battery WTB.

The polarity of current supplied at this time from battery WTB to the track rails is such as to cause relays WTR and ETR to operate their polar contacts to their reverse and normal positions, respectively, whereupon relays AR and WTPR become deenergized and relay WTPR immediately releases to disconnect battery WTB from the track rails, while relay ETPR becomes energized and picks up at the end of its slow pick-up period to connect battery ETB in circuit with the rails. This cycle of operation is repeated as long as the section remains unoccupied.

When a train enters the section, relay ETR is caused to operate to its reverse or right-hand position in response to energy derived from its associated source ETB, while relay WTR is likewise caused to operate to its reverse or right-hand position in response to energy derived from battery WTB. Both relays WTPR and ETPR release to disconnect both batteries WTB and ETB from the track rails, but battery WTB is reconnected to the rails when relay AR releases to energize coder relay RCR. The coder relay RCR functions as a code initiating means and intermittently closes its front contact 23 to connect intermittently battery WTB to the track rails so that when the train vacates the section and front contact 23 of coder relay RCR is closed, a code initiating pulse of energy is available in the section rails to operate relay ETR to its normal or left-hand position. When this happens, relay ETPR becomes energized, and source ETB is connected to the rails for energizing both relays WTR and ETR and for initiating the cycle of operation previously mentioned in detail. This cyclic operation of the track relays ETR and WTR may be detected by means of relays HR and FSA associated with the track relays and arranged as shown provided for relay ETR in Fig. 1.

In Fig. 3, the apparatus illustrated in Fig. 2 is represented modified by incorporating the track relays WTR and ETR in the respective first and second track circuit, in multiple with the source of such circuit. For example, in the normal condition of the apparatus, as represented in the drawings, battery ETB is connected over front contact 17 of relay ETPR to its associated relay ETR in multiple with the rails 1 and 1a and the other track relay WTR. An impedance 25 interposed in the circuit of relay ETR prevents that relay from establishing a short circuit across the rails 1 and 1a, whereas impedance 26 interposed in the circuit of relay WTR is at this time

shunted over an obvious circuit path including back contact 23 of coder relay RCR and back contact 24 of relay WTPR. Relays ETR and WTR are both effectively energized and are caused to swing their respective polar armatures from the illustrated positions to their other positions, whereupon relay ETPR releases to disconnect battery ETB from the track circuit and to shunt impedance 25, while relay WTPR picks up to open the shunt path on impedance 26, and to connect battery WTB to relay WTR in multiple with the track rails and relay ETR. The polarity of current supplied from battery WTB causes both relays ETR and WTR to operate their respective armatures, whereupon relay WTPR releases and relay ETPR picks up. This cycle of operation is maintained as long as the section is unoccupied.

The apparatus of Fig. 3 operates in response to a train in the section in a manner corresponding to that pointed out hereinbefore with reference to the apparatus of Fig. 2, and further detailed description of the apparatus of Fig. 3 is believed to be unnecessary, except to point out that contrary to Fig. 2, like terminals of batteries ETB and WTB are connected to different rails of the section, hence when battery ETB is connected to the track circuit one rail is made positive with respect to the other, whereas when battery WTB is connected to the track circuit, the other rail is made positive with respect to the one rail. The apparatus of Fig. 3 accordingly functions to generate two sets of code impulses, one having one polarity and the other having the opposite polarity.

The apparatus illustrated in Fig. 4 represents a still further modification of the apparatus of Fig. 1, wherein means are provided for attaining two-block, three-indication control of traffic by incorporating means for varying the intervals between successive impulses of energy supplied from at least one of the sources, and by means utilized for detecting the differences in such intervals. Specifically, the apparatus of Fig. 4 corresponds to that of Fig. 1 except that the apparatus is represented applied to a stretch of track over which traffic normally moves in the direction indicated by the arrow in Fig. 4, or from left to right as viewed in the drawings; relay WTR has associated therewith an additional relay DR, energized over a circuit extending from terminal B through normal polar contact 30 of relay WTR, front contact 31 of relay HR1 and the winding of relay DR to terminal C, for detecting short intervals between successive impulses of energy from battery ETB; a three-position signal S controlled by relays HR1 and DR is provided adjacent to entrance end D of the section for governing traffic in the normal direction in the section; and a slow pick-up relay 2HP is provided at the exit end of the section. Relay 2HP is energized over an obvious circuit extending from terminal B through normal polar contact 32 of relay ETR, back contact 33 of relay HR3 associated with the section next in advance of section D-E, and the winding of relay 2HP to terminal C. Relay 2HP when energized provides relay ETPR with an obvious alternate energizing circuit which includes front contact 37 of relay 2HP.

The apparatus of Fig. 4 operates in a manner substantially corresponding to that pointed out in detail in connection with the apparatus of Fig. 1, with the following modifications. When section D-E and the section in advance are unoccupied, relay HR3 of the advance section is picked

up to close its front contact 33, whereupon relay ETPR repeats the action of relay ETR and relatively short intervals intervene between successive connections of battery ETB to the track rails. Relay DR of section D—E at this time is provided with slow pick-up characteristics and is adjusted to pick up only when contact 30 of relay WTR closes a relatively large number of times per minute due to the relative short intervals between successive impulses from battery ETB. Relay HR1 also is picked up, and lamp G of signal S accordingly is caused to be energized over an obvious circuit including front contact 35 of relay HR1, front contact 36 of relay DR and the filament of lamp G of signal S to terminal C.

When the section in advance of section D—E is occupied, relay HR3 associated with such section is released, relay 2HP is energized each time contact 15 of relay ETR is closed in its normal position; and at the end of its slow pick-up period, relay 2HP picks up to energize relay ETPR and thereby connect battery ETB to the track rails. The slow pick-up interval of relay 2HP is now introduced into and added into the interval between successive impulses of energy from battery ETB, hence these intervals between impulses are relatively longer than the intervals between impulses when relay HR3 of the advance section is picked up. The number of impulses transmitted in any given time is now less than when relay HR3 of the advance section is picked up, with the result that relay DR at the entrance end of section D—E is caused to be released, thereby conditioning the associated signal to display a caution aspect due to the energization of lamp Y over an obvious circuit extending from terminal B through front contact 35 of relay HR1, back contact 36 of relay DR and the filament of lamp Y of signal S to terminal C.

When section D—E is occupied and relay WTR is inactive, relays HR and DR associated therewith are released and signal S is caused to display a stop aspect in response to the energization over an obvious circuit of lamp R of signal S.

From the foregoing, it is readily apparent that I have provided novel and improved railway traffic controlling signal systems of the type employing coded energy and in which the apparatus is arranged to eliminate the necessity for a code transmitter, thereby providing a code system wherein each one of two sets of code impulses supplied to a pair of conductors is generated in response to the other set of code impulses.

Although I have herein shown and described only a few forms of railway traffic controlling apparatus embodying my invention, it is understood that various changes and modifications may be made therein within the scope of the appended claims without departing from the spirit and scope of my invention.

Having thus described my invention, what I claim is:

1. In combination, a section of railway track, two polar track relays one at each end of said section, a first slow releasing relay energized when one of said track relays is in a given position, a second and a third slow releasing relay for the other of said track relays, a polarized relay for said other track relay, a normal energizing circuit for said polarized relay including a contact closed in a given position of said other track relay, a reverse energizing circuit for said polarized relay including a contact closed in the other position of said other track relay and a front contact of said second slow releasing relay, an alternate

normal energizing circuit for said polarized relay including a contact closed in said other position of said other track relay and back contacts of each of said second and third slow releasing relays, an energizing circuit for said second slow releasing relay including a contact closed in said other position of said other track relay and a polar contact operated by said polarized relay and closed when that relay is energized in its normal direction, an alternate path in said last-mentioned circuit including a front contact of said third slow releasing relay connected around the polar contact of said polarized relay, an energizing circuit for said third slow releasing relay including a polar contact closed in said given position of said other track relay and a front contact of said second slow releasing relay, a first source of current for said one track relay and a second source of current for said other track relay; a first track circuit for said section including in series said second source, the track rails, the windings of said two track relays, a front contact of said first slow releasing relay and a polar contact of said polarized relay closed in the normal position thereof, said second source being poled to supply current effective to cause said track relays to operate from said given to said other positions; and a second track circuit for said section comprising in series said first source, the track rails, the windings of said two track relays, a back contact of said first slow releasing relay and a polar contact of said polarized relay closed when that relay is energized over a reverse circuit, said first source being poled to supply current having a polarity effective to cause said track relays to operate from said other to said given positions.

2. In combination, a section of railway track, two polar track relays one at each end of said section and each having a first and a second position, a slow pick-up repeater relay for each track relay, means for energizing one of said repeater relays when the associated one track relay is in its said first position, means for energizing the other of said repeater relays when the associated other track relay is in its said second position, a source of current for each of said repeater relays, circuit means rendered effective when said one repeater relay is picked up and said other repeater relay is released for connecting said two track relays in circuit over the track rails to the one source associated with said one repeater relay, said one source being poled to supply current having a relative polarity effective to operate each of said track relays to its said second position, and circuit means rendered effective when said one repeater relay is released and said other repeater relay is picked up for connecting said two track relays in circuit over the track rails to the other source associated with the other of said repeater relays, said other source being poled to supply current having a relative polarity effective to operate each of said track relays to its said first position.

3. In combination, a section of railway track, two polar track relays one at each end of said section and each having a given and another position, a slow pick-up repeater relay for each track relay, means for energizing one of said repeater relays when the associated one track relay is in its said given position, means for energizing the other of said repeater relays when the associated other track relay is in its said other position, a source of current for each of said repeater relays, circuit means rendered effective when said one repeater relay is picked up and said other re-

repeater relay is released for connecting said two track relays in circuit over the track rails to the one source associated with said one repeater relay, said one source being poled to supply current having a relative polarity effective to operate each of said track relays to its said other position, circuit means rendered effective when said one repeater relay is released and said other repeater relay is picked up for connecting said two track relays in circuit over the track rails to the other source associated with the other of said repeater relays, said other source being poled to supply current having a relative polarity effective to operate each of said track relays back to its said given position, an additional slow release repeater relay for one of said track relays, a coding device energized over a back contact of said additional repeater relay, and means controlled by contacts of said coding device for intermittently impressing energy from the associated one of said sources to the track rails and said two track relays.

4. In combination, a section of railway track, two polar track relays one at each end of said section and each having a given and another position, two slow pick-up repeater relays one for each track relay, means for energizing one of said repeater relays when the associated one track relay is in its said given position, means for energizing the other of said repeater relays when the associated other track relay is in its said other position, two sources of current one for each of said repeater relays, circuit means rendered effective when said one repeater relay is picked up and said other repeater relay is released for connecting the one source associated with said one repeater relay to said one track relay in multiple with a circuit path comprising the track rails and said other track relay, said one source being poled to supply current having a relative polarity effective to cause each track relay to operate its armature to its said other position, and circuit means rendered effective when said one repeater relay is released and said other repeater relay is picked up for connecting the said other source to said other track relay in multiple with a circuit path comprising the track rails and said one track relay, said other source being poled to supply current having a polarity effective to cause said track relays to operate back to said given positions.

5. In combination, a section of railway track, two polar track relays one at each end of said section and each having a given and another position, two slow pick-up repeater relays one for each track relay, means for energizing one of said repeater relays when the associated one track relay is in its said given position, means for energizing the other of said repeater relays when the associated other track relay is in its said other position, two sources of current one for each of said repeater relays, circuit means rendered effective when said one repeater relay is picked up and said other repeater relay is released for connecting the one source associated with said one repeater relay to said one track relay in multiple with a circuit path comprising the track rails and said other track relay, said one source being poled to supply current having a relative polarity effective to cause each track relay to operate its armature to its said other position, circuit means rendered effective when said one repeater relay is released and said other repeater relay is picked up for connecting the said other source to said other track relay in multiple with a circuit path comprising the track

rails and said one track relay, said other source being poled to supply current having a polarity effective to cause said track relays to operate back to said given positions, a current limiting resistor connected in series with the winding of each of said track relays, and means effective when a repeater relay is released for establishing a shunt path around the resistor of its associated track relay.

6. In combination, a section of railway track, two polar track relays one at each end of said section and each having a given and another position, two slow pick-up repeater relays one for each track relay, means for energizing one of said repeater relays when the associated one track relay is in its said given position, means for energizing the other of said repeater relays when the associated other track relay is in its said other position, two sources of current one for each of said repeater relays, circuit means rendered effective when said one repeater relay is picked up and said other repeater relay is released for connecting the one source associated with said one repeater relay to said one track relay in multiple with a circuit path comprising the track rails and said other track relay, said one source being poled to supply current having a relative polarity effective to cause each track relay to operate its armature to its said other position, circuit means rendered effective when said one repeater relay is released and said other repeater relay is picked up for connecting the said other source to said other track relay in multiple with a circuit path comprising the track rails and said one track relay, said other source being poled to supply current having a polarity effective to cause said track relays to operate back to said given positions, an additional slow releasing repeater relay for one of said track relays, means for energizing said slow releasing repeater relay when said one track relay is in its said other position, a coding device energized over a back contact of said slow releasing repeater relay, and circuit means effective when both of said slow pick-up repeater relays are released and controlled by said coding device for intermittently impressing said one source to said one track relay in multiple with said track rails and said other track relay.
7. In combination, a section of railway track, two polar track relays one at each end of said section and each having a given and another position, two slow pick-up repeater relays one for each track relay, means for energizing one of said repeater relays when the associated one track relay is in its said given position, means for energizing the other of said repeater relays when the associated other track relay is in its said other position, two sources of current one for each of said repeater relays, circuit means rendered effective when said one repeater relay is picked up and said other repeater relay is released for connecting the one source associated with said one repeater relay to said one track relay in multiple with a circuit path comprising the track rails and said other track relay, said one source being poled to supply current having a relative polarity effective to cause each track relay to operate its armature to its said other position, circuit means rendered effective when said one repeater relay is released and said other repeater relay is picked up for connecting the said other source to said other track relay in multiple with a circuit path comprising the track rails and said one track relay, said

other source being poled to supply current having a polarity effective to cause said track relays to operate back to said given positions, an additional slow releasing repeater relay for one of said track relays, means for energizing said slow releasing repeater relay when said one track relay is in its said other position, a coding device energized over a back contact of said slow releasing repeater relay, circuit means effective when both of said slow pick-up repeater relays are released and controlled by said coding device for intermittently impressing said one source to said one track relay in multiple with said track rails and said other track relay, two current limiting resistors one connected in series with the winding of each of said track relays, a circuit completed through a back contact of said other slow pick-up repeater for shunting the resistor of the associated other track relay, and a circuit completed through a back contact of said coder and a back contact of said one slow pick-up relay for shunting the resistor of the associated one track relay.

8. In combination, a section of railway track, two track relays one for each end of said section, two sources of current one for each section end, a first track circuit for said section comprising the source at a given section end and the track rails and the windings of both of said track relays, means controlled by the track relay at the opposite section end effective each time when energized over said first track circuit to open such circuit and complete a second track circuit comprising the other source at said opposite section end and said track rails and said windings of said track relays, means controlled by the track relay at said given section end effective each time when energized over said second track circuit to open such circuit and complete said first track circuit, and means governed by the track relay at said given section end for controlling traffic entering said section at such section end.

9. In combination, a stretch of railway track including a track section, two track relays one for each end of said section, two current sources one for each section end, a first track circuit for said section comprising the source at a given section end and the section rails and the windings of both of said track relays, means governed by the track relay at the opposite end of the section effective each time when energized over said first track circuit to open such circuit and complete a second track circuit comprising the other source at said opposite section end and the section rails and the windings of both track relays, means controlled by the track relay at said given section end effective each time when energized over either said first or said second track circuit to open the respective circuit, additional means at said opposite section end governed by traffic conditions on said stretch beyond that section end for completing said first track circuit at the end of one or another predetermined time interval dependent upon traffic conditions on said stretch, and means controlled by said given section end track relay for governing traffic in said section and responsive selectively to the different intervals existing between successive completions of said first track circuit.

10. In combination, a stretch of railway track including a track section, two track relays one for each end of said section, two current sources one for each section end, a first track circuit for said section comprising the source at a given section end and the section rails and the windings of

both of said track relays, means governed by the track relay at the opposite end of the section effective each time when energized over said first track circuit to open such circuit and complete a second track circuit comprising the other source at said opposite section end and the section rails and the windings of both track relays, means controlled by the track relay at said given section end effective each time when energized over either said first or said second track circuit to open the respective circuit, additional means at said opposite section end governed by traffic conditions on said stretch beyond that section end for completing said first track circuit at the end of one or another predetermined time interval dependent upon traffic conditions on said stretch, means controlled by said given section end track relay for governing traffic in said section and responsive selectively to the different intervals existing between successive completions of said first track circuit, control means controlled by said given section end track relay for detecting the successive energization of such track relay alternately over said first and second track circuits, and for distinguishing between the different intervals existing between successive completions of said first track circuit, and means at the said given section end controlled by said control means for governing traffic entering said section at said given section end.

11. In combination, a section of railway track, two polarity responsive track relays one for either end of said section and each having a given position and another position, two controlled relays one for each track relay and each having a first position and a second position, means controlled by each track relay for operating the associated controlled relay to its said first position or said second position according as the track relay is in its said given position or said other position, two sources of current one for each section end, a first track circuit for said section including the source at a given section end and the track rails and the windings of both of said track relays and first position contacts of each of said controlled relays, said given section end source being poled to cause operation of each of said polarity responsive track relays from its said given position to said other position, a second track circuit for said section including the source at the opposite section end and the track rails and the windings of both of said track relays and second position contacts of each of said controlled relays, said opposite section end source being poled to cause each of said polarity responsive track relays to operate from its said other position to its said given position, and means controlled by one of said track relays when reversible operation thereof is terminated by the shunting action of a train in the section for applying to the track rails code impulses of energy from the source at the associated end of the section.

12. In combination, a section of railway track, two polarity responsive track relays one for either end of said section and each having a given position and another position, two controlled relays one for each track relay and each having a first position and a second position, means controlled by each track relay for operating the associated controlled relay to its said first position or said second position according as the track relay is in its said given position or said other position, two sources of current one for each section end, a first track circuit for said section including the source at a given section end and the track rails

and the windings of both of said track relays and first position contacts of each of said controlled relays, said given section end source being poled to cause operation of each of said polarity responsive track relays from its said given position to said other position, a second track circuit for said section including the source at the opposite section end and the track rails and the windings of both of said track relays and second position contacts of each of said controlled relays, said opposite section end source being poled to cause each of said polarity responsive track relays to operate from its said other position to its said given position, and means controlled by one of said track relays effective when said section is occupied by a train for operating the associated controlled relay alternately to its said first and second positions, whereby intermittently to impress the source at the associated section end across the track rails of said section.

13. In combination, a section of railway track, two polarity responsive track relays one for either end of said section and each having a given position and another position, two controlled relays one for each track relay and each having a first position and a second position, means controlled by each track relay for operating the associated controlled relay to its said first position or said second position according as the track relay is in its said given position or said other position, two sources of current one for each section end, a first track circuit for said section including the source at a given section end and the track rails and the windings of both of said track relays and first position contacts of each of said controlled relays, said given section end source being poled to cause operation of each of said polarity responsive track relays from its said given position to said other position, a second track circuit for said section including the source at the opposite section end and the track rails and the windings of both of said track relays and second position contacts of each of said controlled relays, said opposite section end source being poled to cause each of said polarity responsive track relays to operate from its said other position to its said given position, and means controlled by the track relay at one end of said section, effective when energy from the source at the other section end is shunted away from such track relay by a train in said section, for operating the controlled relay

5 associated with such track relay alternately to its said first and said second positions whereby to impress intermittently on the track rails the source at said one section end.

14. In combination, a section of railway track, two polarity responsive track relays one for either end of said section and each having a given position and another position, two controlled relays one for each track relay and each having a first position and a second position, means controlled by each track relay for operating the associated controlled relay to its said first position or said second position according as the track relay is in its said given position or said other position, control means associated with one of said track relays and controlled by traffic conditions beyond the end of the section at which said one track relay is located for at times delaying the operation of the associated controlled relay from one of its positions to the other following the operation of said one track relay from one position to the other, two sources of current one for each section end, a first track circuit for said section including the source at a given section end and the track rails and the windings of both of said track relays and first position contacts of each of said controlled relays, said given section end source being poled to cause operation of each of said polarity responsive track relays from its 15 said given position to said other position, a second track circuit for said section including the source at the opposite section end and the track rails and the windings of both of said track relays and second position contacts of each of said controlled relays, said opposite section end source being poled to cause each of said polarity responsive track relays to operate from its said other position to its said given position, means associated with the other of said track relays responsive to reversible operation of that track relay and other means associated with that track relay selectively responsive to reversible operation of that track relay when operation of said one track relay's associated controlled relay is delayed by said control means, and means controlled by one of said track relays when reversible operation thereof is terminated by the shunting action of a train in the section for applying to the track rails code impulses of energy from the source at the associated end of the section.

JOHN M. PELIKAN.
